[57] CLAIM

The ornamental design for a motorhome connection, as shown and described.

DESCRIPTION

FIG. 1 is a front elevational view of a motorhome connection showing my new design;

FIG. 2 is a left side elevational view thereof, the right side being a mirror image of the left side;

FIG. 3 is a rear elevational view thereof;

FIG. 4 is a top plan view thereof; and,

FIG. 5 is a bottom plan view thereof.

Fig. 1.

Fig. 3.

Fig. 2.

Fig. 4.

Fig. 5.
